UNITED STATES PATENT OFFICE.

EDWARD S. LEVY, OF NEW YORK, N. Y.

NECKTIE.

1,280,773.

Specification of Letters Patent.

Patented Oct. 8, 1918.

Application filed February 15, 1915. Serial No. 8,213.

To all whom it may concern:

Be it known that I, EDWARD S. LEVY, a citizen of the United States, and resident of the borough of Manhattan, city, county, 5 and State of New York, have invented certain new and useful Improvements in Neckties, of which the following is a specification.

In the manufacture of neckwear, and especially four-in-hand scarfs, it is found necessary to use a soft flannel interlining in order to give the scarf the necessary thickness or body in the tying ends. This is especially necessary where the scarfs are made of very thin and soft material such as silk 10 crape. Four-in-hand scarfs are usually made with one tying end larger than the other, the larger tying end being the one used in forming the knot when the scarf is in use. In four-in-hand scarfs made of soft 15 thin material, such as silk crape, the soft flannel interlining in the larger tying end soon becomes twisted and curled within the tie. This, of course, distorts the tie and renders it unsightly. This is a great objection to ties of this character, and such objection or defect interferes materially with their sale, particularly as these scarfs are made of expensive material and retail at a 20 comparatively high price. It is of prime importance that neckwear, and particularly the larger tying end of a four-in-hand scarf, 25 shall keep its shape. Users of high-priced neckwear will not wear an unsightly and distorted scarf, and silk crape scarfs, as heretofore manufactured, are pulled out of 30 shape long before the material shows any 35 signs of wear or use.

It is the main object of this invention to provide a simple means to prevent the soft 40 interlining in the scarf from being curled or twisted.

A further object of the invention is to secure either or both ends of the interlining to the back fold of the scarf by means of a 45 transverse line of stitches which passes through the lining and through the back fold only of the scarf so that said line of 50 stitches will not show on the front or face of the scarf, said line or lines of stitches extending substantially throughout the width 55 of the lining at the end thereof and near the end of the scarf. It is manifest that the lining may be secured to the back fold of the 60 scarf in any other suitable manner, but it is 65 essential that the securing means extend 70 transversely of the scarf throughout the

width of the lining at the point of attachment.

In the drawing, Figure 1 is a view of the back fold of a four-in-hand scarf showing 60 the interlining secured to the back fold thereof by lines of stitches which follow substantially the margin of the end of the scarf;

Fig. 2 a similar view of one end of a scarf 65 showing the line of stitches oblique to the center line of the scarf;

Fig. 3 a similar view showing the line of 70 stitches extending across the scarf at right angles to the center line thereof; and

Fig. 4 a transverse sectional view of the 75 end of the scarf showing the stitches passing through the back fold of the scarf and the interlining.

Referring to the various parts by numerals, 1 designates the back fold of the scarf, 2 the face or front fold thereof and 3 the soft flannel interlining. These four-in-hand scarfs are usually constructed of a piece of silk cut and folded so that the 80 edges are joined in a seam extending longitudinally of the back fold of the scarf. The material is cut and folded to form the narrow neckband portion 4 and the outwardly flaring or enlarged tying end portions 5 85 and 6, the tying end 6 being larger than the end 5. The interlining 3 is usually cut to conform to the shape of the scarf, said lining extending from the neckband portion throughout the tying ends and terminating 90 near the ends of the scarf. The outer ends of the interlining are usually the widest parts thereof and are approximately equal in width to the width of the scarf.

To hold the interlining flat within the 95 scarf and to prevent it curling and twisting under the strain applied to the scarf when tying it into a knot and adjusting it to the collar, I secure the end of the interlining to the back fold only of the scarf by a line 100 of stitches 7. This line of stitches preferably follows the edge of the interlining at the end thereof, and extends transversely across the back fold of the scarf and throughout the entire width thereof. As heretofore 105 pointed out the interlining is widest at its ends and is nearly equal in width to the width of the scarf so that the said line of stitches 7 extends practically throughout the width of the scarf. It is immaterial whether 110 this line of stitches 7 is arranged in oblique lines which converge toward the end of the

scarf, as shown in Fig. 1, or whether they extend obliquely across the entire end of the scarf, as shown at 7^a in Fig. 2, or extend across the end of the scarf at right angles to the longitudinal center line thereof, as shown at 7^b in Fig. 3. These stitches 7 extend through the interlining and the back fold only of the tie as shown clearly in Fig. 4, so that the face of the tie is not in any way disfigured.

By running the line of stitches 7 across the widest part of the interlining the entire interlining is held flat against the back fold of the tie and prevented from curling. It is manifest that by holding the wide end of the interlining flat the reduced portions thereof cannot curl. This curling naturally starts at the widest end of the interlining in the old type of scarfs where the interlining was not attached as described herein.

What I claim is:

A necktie comprising a flat tubular body formed with a narrow neckband portion and

outwardly flaring tying-end portions, the longitudinal meeting edges of the tubular body being stitched together along the middle of the back fold of the tie, an interlining strip extending through the tubular body substantially from end to end thereof and conforming substantially to the shape and width of the flattened tubular body, said interlining strip being secured to the body solely by transversely extending lines of stitches extending across said strip from edge to edge thereof adjacent each end and across the longitudinal seam extending along the middle of the back fold of the body, said transverse lines of stitches passing through only the interlining and the back fold of the flattened tubular body.

In testimony whereof I hereunto affix my signature in the presence of two witnesses.

EDWARD S. LEVY.
